CLIP FOR CONNECTING ENDS OF PLASTIC STRIP ACROSS FURNITURE FRAMES

James John Mirrione, Brooklyn, N.Y., assignor to J.F.D.
Manufacturing Co., Inc., Brooklyn, N.Y., a corpora-
tion of New York

Filed Nov. 30, 1960, Ser. No. 63,046

Term of patent 14 years

(Cl. D17—3)

FIG. 2.

FIG. 3.

FIG. 4.

Fig. 1 is a top plan view of a clip for connecting ends of plastic strip across furniture frames showing my new design;

Figure 2 is a side elevational view thereof;

Figure 3 is a bottom plan view; and

Figure 4 is a cross-sectional view as taken along the line 4-4 of Figure 1.

I claim:

The ornamental design for a clip for connecting ends of plastic strip across furniture frames, substantially as shown.
